Primary Examiner — Elizabeth J Oswecki

(57) **CLAIM**

The ornamental design for a safe door with a door pull, hinging and door casing, as shown and described.

DESCRIPTION

FIG. 1 is a perspective view of a safe door with door pull, hinging and door casing showing my new design;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof; and,

FIG. 8 is another perspective view thereof.

The broken lines shown in the drawings represent portions of the safe door with door pull, hinging and door casing that form no part of the claimed design.
